Primary Examiner — Kevin K Rudzinski*Assistant Examiner* — Paul D Bohannon(74) Attorney, Agent, or Firm — Scully, Scott, Murphy & Presser, P.C.(57) CLAIM

The ornamental design for a furniture, as shown and described.

DESCRIPTION

FIG. 1 is a perspective view of a furniture showing our new design;

FIG. 2 is a front view;

FIG. 3 is a rear view;

FIG. 4 is a left side view;

FIG. 5 is a right side view;

FIG. 6 is a top view;

FIG. 7 is a bottom view;

FIG. 8 is a further perspective view; and,

FIG. 9 is a further perspective view.

The broken lines shown in the drawings are for the purpose of illustrating portions of the furniture and form no part of the claimed design.
